LAUNDRY RECEPTACLE

Samuel Katzman, Brooklyn, N. Y.

Application April 11, 1929, Serial No. 354,377

4 Claims. (Cl. 232—1)

My invention relates to receptacles, also known as hampers, for the reception of soiled articles to be laundered, which are deposited therein from time to time and collectively removed therefrom periodically for the purpose of being laundered.

- An object of my invention is the provision of a neat-looking and sanitary laundry receptacle having one opening which is readily accessible for the inserting therethrough of the soiled articles, and having another opening to which easy access may be had for the removal therethrough of the collected articles for the purpose of being laundered.
- Another object is the provision of a laundry receptacle for use in private homes, hotels and the like, which is capable of being placed in a basement, bathroom, hall or any other desirable and convenient location for the collection of soiled laundry.

One feature of my invention is the provision of a separate compartment in the laundry receptacle for collecting small articles, such as handkerchiefs, collars, stockings, etc., thereby keeping same apart from the larger articles, such as shirts, underwear, bedsheets, towels, etc. With this feature there is obviated the necessity of sorting the laundry at the time it is removed from the receptacle and delivered to the laundryman to be laundered, with the consequent saving of time and trouble.

Other objects and features of the invention will appear from the following description of an embodiment of the invention shown merely for purpose of affording an understanding of the invention, and not for imposing limitations thereon.

- In the accompanying drawing forming a part hereof:
- The figure is a perspective of one form of device constructed according to and embodying my said invention.

Referring to the drawing, the device comprises a container 10 having front, back, and lateral walls 12, 14 and 16, and open at the upper end, as indicated at 18, through which the soiled articles are received. The container 10 is preferably of greater height than width and depth, and rectangular in cross-section.

- One wall, preferably wall 12, at the upper portion thereof is provided with a portion or panel 20 for ventilating the interior, preferably consisting of an opening covered by a reticulated or foraminated grille 22 or the like, and said wall at the lower portion thereof is provided with an

opening 24, larger than the opening 18, through which the collected soiled articles are withdrawn. The opening 24 is normally closed by the door 26 hinged on a vertical axis 28, the door in the closed position thereof lying in the plane of the front wall and swinging outwardly and laterally out of the way, as indicated in broken lines, to permit of the removal of the articles. The door 26 is retained in closed position by a suitable latch 30.

A separate compartment 32 is formed within the receptacle 10 at one side of the upper portion thereof above the opening 24 for receiving smaller articles of laundry such as collars, handkerchiefs, stockings, and the like.

The compartment 32 is open at the top, as indicated at 34, to permit of the reception of the smaller articles, and a part of the ventilating portion 20 serves as the front wall thereof, the main chamber 36 and the compartment 32 being ventilated by the common portion 20.

The article receiving opening 34 into the compartment 32 and the opening 18 into the main chamber 36 are normally closed by the common door 38 hinged at 40 upon a transverse horizontal axis, and capable of being swung back out of the way, as indicated in broken lines. The door 38 is provided with a knob 42.

If desired, the inner walls of the receptacle may be provided with hooks and a laundry bag 85 of canvas, or any other suitable material, attached in open position within the receptacle on said hooks, so that when soiled laundry is deposited in said receptacle it will fall into and be collected in said bag, and when it is desired to empty the laundry receptacle for the purpose of laundering the articles collected therein, the entire contents of the receptacle may be conveniently removed at one time by simply detaching and removing from the receptacle the bag 95 containing the collected laundry.

The laundry receptacle of the present invention may be made in any shape or size, and may be constructed of sheet metal, wood, fibre or any other suitable material.

It will be apparent from the foregoing that the laundry receptacle of my invention has a neat and pleasing appearance, is very sanitary, constitutes a great convenience wherever used, and enables a saving of time and trouble, which the busy housekeeper can particularly appreciate.

I claim:

1. A laundry receiving device comprising a container having an opening at the top thereof through which articles to be laundered are re-

- ceived into the container, and an opening in the lower portion of a vertical wall thereof through which the received articles are removed, said container from the upper opening to the lower 5 one forming a continuously open passage of sufficient capacity to permit of the articles freely dropping to the bottom thereof and accumulating therein, a compartment open at the top disposed within the confines of the wall portions of said 10 container forming said passage and occupying a portion of the space within the container at the upper portion thereof above the lower opening, the remaining portion of the space at the upper portion providing passage for the soiled 15 articles past said compartment into the lower portion of the container, a closure common to said top openings, and a closure for the lower opening.
2. A laundry receiving device comprising a receptacle open at the top for the reception of the larger soiled articles, and having an opening at the lower portion of a vertical wall thereof for the removal of the accumulated soiled articles, 20 said container from the upper opening to the lower one forming a continuously open passage of sufficient capacity to permit of the articles freely dropping to the bottom thereof and accumulated therein, a separate compartment disposed within the confines of the passage forming 25 wall portions of said container above the lower opening and being open at the top, said compartment occupying a portion of the space within said receptacle, and the remaining portion of said space contiguous to said compartment constituting a part of said first named passage for 30 passing the soiled articles past said compartment into the lower portion of the container, a ventilating portion on a vertical wall of said container providing communication from the outside with the interior of said container and said compartment, a closure common to said top and com- 35
- partment openings, and a closure for said lower opening.
3. A laundry receiving device comprising a container having an upper opening therein through which articles to be laundered are received into the container, and a lower opening through which the articles are removed, a compartment for receiving smaller articles of laundry disposed within the confines of the walls of said container at the upper end thereof above the lower opening, being of reduced depth and width relative to the space in said container, and having an opening registering with said first named opening, said container and said compartment forming a continuously open passage reduced at 40 the upper portion thereof and enlarged at the lower portion thereof, and having sufficient capacity to allow the articles to freely drop into the enlarged portion of the passage, a closure common to said upper opening and the opening of said compartment, and a closure for said lower opening.
4. A laundry receiving device comprising a container open at the top for the reception of the larger soiled articles, and having an opening at 45 the lower portion of a vertical wall thereof for the removal of the accumulated soiled articles, said container from the top opening to the lower opening forming a continuously open passage of sufficient capacity to allow the articles to 50 freely drop to the bottom, a ventilating portion in said vertical wall above the lower opening, an L-shaped member disposed within said container at the top thereof and forming with the wall portions thereof, including said ventilating portion, a compartment open at the top and of reduced depth and width relative to the passage in said container, a closure for said lower opening, and a closure common to said top opening and said compartment.
